UNITED STATES PATENT OFFICE

ALONZO P. INGRAM, OF PITTSBURGH, PENNSYLVANIA

DISPENSING, SEVERING, AND MOISTENING APPARATUS

Application filed July 3, 1928. Serial No. 290,130.

This invention relates to apparatus for dispensing and severing continuous strip material such as gummed paper strip and is especially applicable for use in dispensing strips which are gummed at intervals.

It is among the objects of this invention to provide apparatus of the above designated character which shall sever strips in predetermined lengths and which shall moisten the gummed ends of the strip as it is withdrawn from the machine.

Another object of the invention is to provide apparatus in which the strip member is an element which cooperates with the severing mechanism for the purpose of causing the strip to be severed in predetermined lengths and in which the strip itself is the element which initiates the severing operation and the operations following the severing of the strip member.

Another object of the invention is to provide apparatus which shall be adapted for moistening the gummed end of the strip after it is severed and which shall be further capable of automatically feeding the strip for a portion of its travel through the machine.

Still another object of the invention is to provide apparatus of the above designated character which shall be of simple, compact and durable mechanical construction which shall comprise a minimum number of parts that are arranged to make them readily accessible for inspection and renewal, which shall be assembled in a permanent housing to protect them from dust and moisture and which shall be relatively inexpensive to manufacture.

In the accompanying drawings constituting a part hereof and in which like reference characters designate like parts:—

Fig. 1 is a longitudinal sectional view partially in elevation of apparatus embodying the principles of this invention.

Fig. 2 a top plan view thereof with the cover element removed.

Fig. 3 a vertical sectional view taken along the line III—III, Fig. 1.

Fig. 4 a view similar to Fig. 1 showing the severing mechanism in the cut-off position and the moistening element in operative engagement with the strip.

Fig. 5 a side elevational view of a cam member and follower.

Fig. 6 a similar view of a cam element.

Fig. 7 a diagrammatic view of a strip of the kind for which the present apparatus is designed.

Referring to Figs. 1 and 2 of the drawings the structure therein illustrated comprises a base or support 1 having journals 2 for rotatably supporting a shaft 3 which supports a roll 4 of strip material such as paper tape 5, Fig. 7, which is provided with weakened portions or transverse slits 6 at spaced apart intervals and which is further provided with gummed portions 7 adjacent the slits.

Again referring to Fig. 1, the support 1 is provided with a top or cover member 8 which may be permanent or removable and which forms a passage 9 with a sheet metal strip 10 through which passage the end of strip 5 is made to pass.

As shown in Figs. 2 and 3, the cover member 8 may be hinged as at 11 and secured by a wing nut 12 to the support or base 1, thereby rendering the cover member removable for the purpose of providing access to the interior of the apparatus.

Referring to Fig. 3 a shaft 14 is rotatably journalled in the housing support 1 in journals or bushings 15. Secured to the shaft 14 is a spiral spring 16, one end of which is fastened to a spring casing 17. A gear wheel 18 is rotatably journalled on the shaft 14 and is provided with a clutch element 19, Fig. 2, which is adapted to cooperate with a complementary shaped clutch member 20. The

member 20 is operatively connected to rotate with a ratchet wheel 21 that is fixed to rotate with the spring housing 17 so that when the clutch 19-20 is engaged, the spring housing 17 will be the driving member for gear wheel 18.

The gear 18 through an idler gear 18' actuates a gear wheel 23 that is fixed to rotate with a shaft 24 Fig. 3 journalled in bearings 25 which are vertically movable in depending bosses or lugs 26 formed integrally with the cover member 8. As shown in Fig. 1, the bosses 26 are provided with slotted openings 27 in which the bearing members 25 are disposed for vertical movement and the bearing members 25 are biased by coil springs 28 in the direction of the roller 30 thereby assuring the proper operating contact of the rollers 29 and 30 with strip 5.

The shaft 25 carries a frictional roller 29 of rubber or other yielding material which roller cooperates with a flanged roller 30 to intimately engage the paper strip 5 therebetween. The shaft 24 is further provided with a gear wheel 31 on the end opposite to the gear wheel 23. The gear 31 rotates with the shaft 24. The teeth of the gear wheel 31 are adapted to mesh or interact with the teeth of a gear wheel 32 which is rotatably mounted on shaft 14 and provided with a clutch face 33 that cooperates with a clutch face 34 of a movable clutch member which is in sliding engagement with a sleeve element 35 that is rotatably mounted on the shaft 14. Mounted on the sleeve element 35 is a cam 36 having a riser 37 on one side thereof which cooperates with a cam follower 38. Another cam element 39 is rotatably mounted on the sleeve 35 and is provided with a follower 40. The follower 38 is journalled on a stud carried by an arm 41 of a shifting yoke element 42 which is pivotally connected at 43 to a lug 44 projecting upwardly on the base of the support 1, the yoke member 42 being adapted for pivotal movement in response to the movement of the cam follower 38 effected by the cam member 36.

The arms of the yoke member 42 are provided with trunnion members which slidably engage the slotted portions 45 and 46 of clutch members 20 and 34 which members are moved to their clutch making and breaking positions by movement of the yoke 42.

Referring to Figs. 1 and 2, a severing mechanism is mounted in the housing 1 and operates to sever the strip material 5 at intervals by means of the following mechanism:—A cut-off knife 50 is secured to a pair of parallel bars 51 which are pivotally mounted on a fixed shaft 52 to render the knife element 50 vertically movable into a notched or slotted portion 53 of the cover member 8 and through a slotted portion 54 of the partition member 10, the movement of the knife 50

being across the strip material 5 which is severed thereby. The knife 50 is provided with a tongue or pilot member 55 for a purpose to be hereinafter stated.

Secured to the knife 50 is an angle bar 57, the base of which constitutes a seat for a helical spring 58 that rests upon a lug 59 formed on the housing support 1. The knife 50 is normally biased to the upper or cut-off position shown in Fig. 4 by the coil spring 58 but is held in its lower position as illustrated in Fig. 1 by the paper strip 5 and by a latch bar 60. The latter is provided with slotted openings 61 in engagement with pins 62 projecting from an extended portion of the housing member and by means of the slotted engagement with pins 62 the latch bar 60 is rendered movable longitudinally. The bar 60 is biased by a coil spring 63 that is fastened to one of the pins 62 and to a pin 64 in the manner illustrated in Fig. 1. The bar 60 is further provided with a shoulder portion 65 having a tapered edge 66, the shoulder being adapted to engage the knife 50 in the manner shown in Fig. 1. The other end of the bar 60 is provided with a beveled edge 67 for engaging a pawl 68 that is adapted to fit into a notch 69' of the cam 36, Fig. 6. The pin element 64 of the bar 60 is adapted for engagement by a bell crank lever 69 pivoted at 70, the lever being actuated by a depending portion 71 of an arm 72 that is provided with an extension 73 which engages the angle bar 57 of the knife as shown in Fig. 4 for the purpose of cocking knife 50 after it has moved to cut-off position. The lever 72 is actuated by the cam 39 through the follower 40 which is carried by an arm 75 of the lever 72. The ratchet wheel 21 is engaged by a pawl 76 to permit its rotation in one direction only.

The ends of the knife supporting arms 51 are pivotally connected at 77 to a lever 78 carrying a moistener 79. As shown in Fig. 4 the arm 78 carrying the moistener is provided with extensions 80 which are engaged by levers 81 that are biased by spring 82, the object of the spring and lever being to press the moistener 79 against the underside of strip 5 in the manner shown in Fig. 4. The moistener is adapted to be at all time partially submerged in a moistening fluid 83, such as water, which is provided in a container or well 84, placed on a shoulder portion 85 of the member 63'.

The operation of the combined dispensing, severing and moistening apparatus is briefly as follows:—

Referring to Fig. 7, the strip of rolled tape, as previously explained, is gummed at intervals, as indicated at 7, and provided with weakened transverse portions 6, such as perforations or slits, preferably the latter. The end of the strip 5 is passed over the guide roll 4' and between the friction roll 29 and

the flanged roll 30, and it is then disposed through the passage 9 and projected beyond the dispensing side of the apparatus in the manner shown in Fig. 1.

5 The cut-off knife 50 is cocked to the position shown in Fig. 1 and the latch bar 60 pressed with the shoulder 65 against the bottom edge of the knife. The pilot 55 of the knife is supported by the paper strip 5 which 10 acts as an abutment. The pilot is yieldingly urged against the strip by the action of the coil spring 58.

To operate the device the operator engages 15 the projecting portion of strip 5 and draws it out of the passage 9. In doing so, the roll 29 by virtue of its frictional engagement with the strip 5, is rotated and in turn rotates the gear wheel 18 through its gear connection 23. When the mechanism is in the cocked position, as shown in Fig. 1, the clutch elements 20 19 and 20 are in their clutch making position in which position the spring casing 17 is rotated in the direction causing the spring 16 to be wound up, storing up torsional 25 energy.

When the strip 5 has been pulled out to the position where one of the slits 6 of the strip registers with the pilot 55, the knife will automatically rise for a distance corresponding 30 to the length of the pilot which is sufficient to release the latch bar 60 and the latter is drawn by spring 63 in the direction of the roll 4, and in this movement, the lower edge of knife 50 is engaged by the tapered surface 35 66 of the latch bar and forced upwardly, bringing the cutting edge of the knife into engagement with the strip 5 and severing the same on a line in a plane with the slits 6. The bars 51 carrying the knife in their upward movement, will cause the member 73 carrying the moistener to be raised, to bring the moistener into engagement with the end of the strip 5 so that the gummed portions 7 adjacent the cut-off end of the strip will pass 40 45 over the moistener as the strip is withdrawn from the apparatus.

Simultaneously with the backward movement of the latch 60, the pawl 68 is engaged by the latch bar and displaced out of contact with notch 69' of the cam 36. This action causes the following sequence of operations:—

The energy stored up in spring 16 will 55 rotate cams 36 and 39 causing the shifting yoke 42 to break the clutch element 19—20 and make clutching engagement of the elements 33—34 whereby the gear wheel 32 is actuated causing the pinion member 31 to rotate. The pinion 31 being fixed to rotate 60 with the friction roller 29, will cause the latter to revolve and on account of the intimate engagement of the fixed roller with the strip 5 the latter will be advanced through the passage 9 for a distance corresponding 65 to the peripheral movement of the roller 29

which is of such dimension in proportion to its rotary movement effected through the spring release that the strip 5 will project a predetermined distance out of the end of passage 9 as illustrated in Figs. 1, 2 and 4 of the drawings. 70

During the rotation of the sleeve 35 effected by the unwinding of the spring 16, the follower 40 will strike the rise of cam 39, thus raising the arm 75 of lever 72 and depressing the arm on the opposite side of its pivotal support. By this action the depending longitudinal element 71 of lever 72 engages an arm of the bell crank 69 depressing the latter which produces movement of the latch bar 80 75 85 90 95 100 105 110 115 120 125 130 which subjects the spring member 63 to tension and the end 73 of lever 72 at the same time engages the seat of the angle bar 57 and causes the knife 50 to be lowered to its cocked position at the same time depressing the coil spring 58.

When the knife 50 has fallen below the shoulder 65 of the latch bar, it is out of line with the tape element 5 and it is then that the latter is automatically dispensed through the 90 passage 9 as previously explained.

When the apparatus again assumes its normal position, the pilot 55 of the cut-off knife will yieldingly engage the lower edge of the strip 5 and the apparatus is set for the removal of the next strip, which is effected in the same manner as described. 95

It is to be noted that the operation of the severing mechanism is initiated through the slit 6 of the strip material and that the length of strip cut-off by the mechanism is determined by the spacing of the slits in the strip. On account of the fact that the cut-off mechanism cooperates with the strip in a manner to be released when the weakened portion or slit of the strip registers with the pilot of the cut-off knife, the strip element is constituted an element in the operating mechanism and the severing mechanism is thereby rendered positive in its action as it is not dependent upon frictional contact or other variable elements employed in prior art devices. 100 105 110 115 120 125 130

Attention is also called to the coordination of the moistener with the cut-off or severing mechanism by means of which the moistening element is kept out of contact with the strip until the latter has been severed which is at the time the gummed portion of the strip is passing over the region of the moistener. This is another decided advance in apparatus of this kind. 115 120 125

It will be evident from the foregoing description of this invention that dispensing and severing mechanism made in accordance therewith is of simple and relatively inexpensive construction and positive and efficient in its operation of conducting the several functions for which it is intended. 125

Although one embodiment of the improvement has herein been illustrated and de- 130

scribed, it will be obvious to those skilled in the art that various modifications may be made in the details of construction without departing from the principles herein set forth.

5 I claim herein as my invention:

1. Apparatus for dispensing and severing strip material comprising in combination means for supporting a continuous strip having weakened portions at spaced intervals,

10 a severing member in the path of movement of the strip which is adapted to cooperatively and continuously engage said strip, and mechanism adapted to render said severing member operative when a weakened portion of the strip is in alignment with the severing edge.

15 2. Apparatus for dispensing and severing strip material comprising in combination means for supporting a continuous strip having weakened portions at spaced intervals, a severing member in the path of movement of the strip having a pilot for continuous engagement with said strip and mechanism adapted to render said severing member operative when its pilot registers with a weakened portion of the strip.

20 3. Apparatus for dispensing and severing strip material comprising in combination means for supporting a continuous strip having weakened portions at spaced intervals, a severing member in the path of movement of the strip and adapted to yieldingly and continuously engage said strip and means actuating said severing member to cut off the strip when a weakened portion of the latter is in register therewith.

25 4. Apparatus for dispensing and severing strip material comprising in combination means for supporting a continuous strip having transversely disposed perforations, a severing member in the path of movement of the strip, and resilient means for yieldingly holding said member against said strip, said means being operative to cut off said strip when the severing member is in alignment with a perforated portion thereof.

30 5. Apparatus for dispensing and severing strip material comprising in combination means for supporting a continuous strip having weakened portions at spaced intervals, and a severing member biased against said strip and adapted to register with its weakened portions, said strip constituting an 35 abutment for the severing member and said member being adapted to cut off the strip when it registers with a weakened portion thereof.

60 6. Apparatus for dispensing and severing strip material comprising in combination a support for rotatably mounting a roll of strip material and actuating mechanism comprising a torsion spring adapted to be wound through a friction element continuously in 65 contact with the strip material, a severing

mechanism cooperating with said strip and adapted to sever the same at predetermined intervals, and means responsive to the movement of the severing mechanism for releasing the torsion spring whereby the friction element advances the strip for a predetermined distance.

70 In testimony whereof I have hereunto set my hand this 29 day of June, 1928, at Pittsburgh, Pa.
